UNITED STATES PATENT OFFICE

EVERETT CHAPMAN, OF CLEVELAND, OHIO, ASSIGNOR TO THE LINCOLN ELECTRIC COMPANY, OF CLEVELAND, OHIO, A CORPORATION OF OHIO

PORTABLE ELECTRODE HOLDER

Application filed October 21, 1929. Serial No. 401,115.

This invention, as indicated, relates to electrode holders and more particularly to electrode holders of the portable type which are adapted to be grasped in the hand of the operator during the welding process. In the use of the electric arc for metal working or for analogous operations wherein the electrode is moved about by hand, considerable difficulty has been encountered in providing a satisfactory holder for such electrodes, particularly where the latter is in the form of a carbon pencil. An electrode holder capable of ready and easy manipulation by hand must have the essential qualifications of being light in weight and also the movement of such electrode holder must be hampered by as few connections or leads as possible.

It is an object of my invention to provide an electrode holder having the qualifications and advantages above set forth as well as other advantages which will appear as my description proceeds.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a diagrammatic view of the electrode holder embodying the principles of my invention; Fig. 2 is a part section, part elevation of a portion of the device shown in Fig. 1; Fig. 3 is a sectional view taken on the plane indicated by the lines 3—3 of Fig. 2; Fig. 4 is a sectional view taken on the plane indicated by the line 4—4 of Fig. 2; Fig. 5 is part section, part elevation on the planes indicated by the line 5—5 of Fig. 2; Fig. 6 is an enlarged part section and part elevation of a part of the device shown in Fig. 1; Fig. 7 is a part section, part elevation taken on the plane substantially indicated by the line 7—7 of Fig. 6.

Referring more specifically to the drawings and more especially to Fig. 1, the device here

illustrated consists of rigid conduits 1 and 2, one of which is suitably connected to a source of supply (not shown) of a suitable temperature modifying medium, such as water, and the other of which is suitably connected to a means (not shown) for discharging such modifying medium. To the ends 3 and 4 of the rigid conduits 1 and 2, respectively, are connected flexible conduits 5 and 6, said ends 3 and 4 telescopically engaged by such flexible conduits and secured thereto by means of clamping members 7. To the other ends of such flexible conduits 5 and 6 are attached the connecting elements 8 and 9, respectively, which are telescopically secured to such flexible conduits 5 and 6 by means of the clamping elements 10. Suitably connected to the elements 8 and 9 are elbows 11 and 12 which are in turn adapted to receive the coupling elements 13 and 14.

The coupling elements 13 and 14 are respectively connected to the opposite ends 15 and 16 of a tube which has the terminating portions 17 and 18 thereof disposed in a substantially parallel position and which has its medial portion helically formed as at 19. The helically formed portion of the tube has the inner periphery thereof slightly flattened as at 20 to frictionally secure the electrode 21, shown inserted therein in Fig. 1. To the outer surface of the helically formed portion of the tube is attached suitable insulating means 22, which also serves to maintain the respective turns of the helically formed tube in proper position. Suitably attached to the rigid conduits 1 and 2, as shown in Fig. 6, are flexible electric leads 23 which are encompassed by the flexible conduits 5 and 6 and which at their other ends pass through the connecting elements 8 and 9 and which are secured in the walls of the elbows 11 and 12 at 24 and 25, respectively. The rigid conduits 1 and 2 are suitably connected by means having electrical conductivity, such as the element 26 illustrated in Fig. 7 and which is united with such rigid conduits by welding or like means 27, more particularly shown in Fig. 7. To the element 26 is attached an electric lead 28 by means of the especially adapt-

ed end 29 secured to such member 26 by means of the bolt 30.

The portions 17 and 18 of the tube are arranged in substantially parallel relation and are maintained in such relation by means of complementary elements 31 and 32, more clearly shown in Fig. 3. These complementary elements 31 and 32 have formed therebetween an enlarged opening 33 adapted to surround the junctures of the flexible leads and the elements 13 and 14 in order to give adequate protection thereto during rough usage to which such device is necessarily subjected. The complementary elements 31 and 32 are suitably removably united by means of bolts 34. Positioned intermediately of the tubes 17 and 18 and the complementary elements 31 and 32 are suitable insulating means 35, which afford electrical as well as thermal insulation to the elements 31 and 32 with respect to the tube members 17 and 18. These elements 31 and 32 are so formed as to size and contour as to be readily adaptable to be grasped by the hand of the operator. Attached to the elements 31 and 32 at their especially adapted ends 36 by means of bolts 37, is a suitable shield member 38 which has a slot 39 formed therein and through which project the ends of the tube members 17 and 18.

In the operation of this device the operator's hand grasps the tool at 40 and after a circulation of a temperature modifying medium, such as water, has been caused to circulate through the various conduits, the welding arc is struck between the end of the electrode 21 and the work to be welded. The electric current entering the end of the electrode 21 passes upwardly therethrough and into the helically formed portion 19 of the tube elements 17 and 18, passes through such tube elements and into the flexible electric leads 23 at the connections 24 and 25, follows through such flexible leads 23 and into the rigid conduits 1 and 2, from which it passes into the element 26 and into the lead 28 by way of the connection 29, by which it is guided to one pole of the source of supply. The temperature modifying medium introduced into the various conduits circulates through the tubes which are helically formed at 19 to secure the electrode 21, thereby cooling such electrode holder as well as the handle 40 by which such holder is controlled and also serves as a cooling means for the flexible leads 23, which of necessity must carry a high welding current.

A further advantage of this construction is that the flexible electric leads are encompassed by the flexible conduits, thereby reducing in number the necessary appendages to such electrode holder which materially curtail the ease with which such holder is operated. By having a flexible electric lead in both of the flexible conduits the cross sec-

tional area of the leads required to carry the high welding current is thereby increased so as to prevent the possibility of heating such leads.

The manner in which the handle of the device is constructed insures a rigid structure as well as a structure of minimum weight, which is essential in devices of this character. The shield element 38 attached to the ends of the elements 31 and 32 is interposed between the operator's hand and the arc struck between the electrode 21 and the work to be welded and thereby protects the operator's hand from the heat of such arc.

No further description of the manner of use of my improved electrode holder is deemed necessary since the use of a device of this sort is in general well understood. The several adjustments and the mode of operation of the novel parts comprising the device will moreover be readily understood from the foregoing description thereof. The device has been subjected to severe practical tests without the handle 40 becoming uncomfortably warm; in fact, the usual protective mitten may be discarded if desired. Furthermore, due to the fact that the electrode holder is positively cooled throughout its entirety, the life of such holder and its various parts is correspondingly prolonged and the operation, whatever its character, in which the electric arc is being utilized is materially facilitated.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. A welding electrode manipulating tool having electrode gripping means consisting of a thermal and electrical conductive cooling coil having its terminals leading therefrom, flexible conduits associated with the terminals in said coil, and flexible electric conductors in said flexible conduits and secured to the terminals of said coil.

2. In a welding electrode manipulating tool, the combination of electrode gripping means comprising a helically formed tube of electrical and thermal conductivity, the terminals of said tube arranged as a handle for the tool, flexible conduits attached to the ends of said tube, and flexible electric conductors secured to said tube and leading therefrom within said flexible conduits.

3. A welding electrode manipulating tool having electrode gripping means consisting of a helically arranged electrical conductive cooling coil provided with flat areas on the inner periphery of the coil to engage the electrode, the terminals of said coil leading

therefrom in the form of a handle for the tool, flexible conduits attached to said terminals, and flexible electric conductors secured to said terminals and leading therefrom within said flexible conduits.

4. A welding electrode manipulating tool having electrode gripping means, a passage cooperating with said gripping means for the circulation of a cooling fluid, flexible conduits for supplying cooling medium to said holder, and electrical conductors for said holder positioned within said conduits.

Signed by me this 18th day of October, 1929.
